UNITED STATES PATENT OFFICE

CHARLES MORGAN DRINKER AND RODMAN M. DRINKER, OF BLOOMSBURG,
PENNSYLVANIA.

SEAL-LOCK.

SPECIFICATION forming part of Letters Patent No. 371,255, dated October 11, 1887.

Application filed June 24, 1887. Serial No. 242,397. (Model.)

To all whom it may concern:

Be it known that we, CHARLES MORGAN DRINKER and RODMAN M. DRINKER, citizens of the United States, residing at Bloomsburg, 5 in the county of Columbia and State of Pennsylvania, have invented a new and useful Improvement in Seal-Locks, of which the following is a specification.

Our invention relates to an improvement in 10 seal-locks; and it consists in a certain novel construction and arrangement of parts fully set forth hereinafter, and specifically pointed out in the claims.

In the accompanying drawings, Figure 1 is 15 a perspective view of the seal-lock. Fig. 2 is a longitudinal section of the same. Fig. 3 is a similar view with the shackle released. Fig. 4 is a reversed plan view of the lock. Fig. 5 is a side view of the key.

20 Referring by letter to the drawings, the body A of our improved seal-lock comprises the head B, having a circular lower side, and the parallel arms C C, formed integrally with the said head, the said head being provided with 25 a vertical central opening, b, for a purpose to be explained. The said head B is provided with a hollow space or opening, B', communicating with the central opening, b, therein, and in the said opening B' is pivoted the dog 30 D, having the lateral arm d extending therefrom, which is adapted, when the said dog is repressed, to compress the spiral spring d', which is disposed between the end of the said arm d and the upper side of the open space or 35 opening B'. The said dog projects out slightly into the central opening, b, in the head, for a purpose hereinafter explained.

c c are depending lugs on the arms C C, near the head, and the said lugs are provided with 40 aligned perforations.

E designates the shackle of the lock, pivoted at its rear end between the extremities of the arms C C, and fitting at the other end in the central opening, b, in the head of the lock. The said rear or pivoted end of the shackle is provided with the angle arm or lug F, formed on the side of the said shackle and extending toward the head of the body of the 45

lock. The arm F is provided with a rabbet or recess, f', on the lower side of the extremity thereof. The locking end of the shackle is provided with the notch e, adapted to receive the dog D, and the narrow slit e', communicating with the said notch and adapted to receive a key to repress the said dog. The said key G is provided with the straight shank g, the lower or engaging end of which is straight on one side, while the other side is beveled to reduce the said shank to a point. The said key is inserted into the slit e' in the end of the shackle, 55 with the straight side thereof toward the dog D, and when the key is pressed in or upwardly the beveled side thereof, sliding on the beveled side of the slit e', presses the said dog out of engagement with the notch and allows the 60 shackle to be opened.

H designates the locking-arm for the seal, and it comprises the lever-arm h, pivoted between the lugs c c on the lower side of the arms, C C and the ring H' on the end thereof, 70 which corresponds in size to the circular lower side or seat of the body of the lock. The said lever-arm extends rearwardly under the lower side of the arm F, which is on the pivoted end of the shackle, and the strong spring I is secured at one end rigidly to the upper side of the lever-arm, near the pivot thereof, and bears at the other end in the rabbet or recess f' in the lower side of the said arm F. It will be 75 seen that the tendency of this spring is to force 80 the extremity of the lever-arm h downwardly, and at the same time to force the arm F of the shackle upwardly, and therefore when the locking end of the shackle is released the spring 85 will cause the said shackle to be thrown back.

It will be seen that when the shackle is locked in place the arm F bears down tightly upon the upper side of the extremity of the lever-arm h, and therefore holds the ring H' at the other end of the said lever-arm tightly 90 pressed against the seat on the under side of the head of the lock. The said seat a is provided around its outer edge with the annular flange a', and the upper edge of the ring H' is beveled on the outer side to fit within the said 95 flange a' on the seat, while the inner edge of

the said ring is rabbeted or recessed, as seen at h' .

K designates the circular seal, which is placed on the seat a , with the edges thereof in 5 in the rabbet h' of the ring, and when the free end of the shackle is pressed into the central opening in the head and locked in position, as shown in Fig. 2, the ring is drawn tightly up to the seat, and thus held rigidly in position.

10 It will be seen that it is impossible for the seal to be extracted after the shackle has been locked, for the beveled upper edge of the ring fits within the annular flange of the seat, and thus prevents the insertion of a tool.

15 The only manner in which the lock can be opened after the seal is locked in place is by forcing the sharpened end of the key through the said seal and inserting it into the slit in the end of the shackle in the manner herein- 20 before described.

25 The construction of our lock is very simple and it is very easily operated by the proper means; but it will be seen that when the seal is secured in place there is no possible way in which the lock can be opened without breaking 30 said seal, as the parts of the lock are made sufficiently strong to resist any ordinary attempts to break or open it.

The opening B' in the head of the lock, containing 35 the locking-dog, is inclosed separately from the other portion of the lock, both to prevent the weather from gaining access to the locking mechanism and to prevent the locking-dog from being tampered with. It 40 will be seen, however, by referring to Fig. 2, that the top plate of the said opening B' is riveted in place, and was so secured after the said locking mechanism was inserted.

45 The lever-arm, as will be seen, is securely riveted in place, and it is not necessary to inclose this portion of the lock, as it is evident that as the under side of the arm F presses down tightly on the extremity of the lever-arm there is no possibility of the ring at the other end of the lever-arm being lifted.

Having thus described our invention, what we claim, and desire to secure by Letters Patent, is—

1. In a seal-lock, the combination, with the 50 body A and the shackle E, of the locking-arm H, adapted to hold the seal in place and be operated by said shackle to release or lock the seal when the shackle is unlocked or locked, substantially as specified.

55 2. In a seal-lock, the combination, with the body A, of the shackle E and the locking-arm H, comprising the lever-arm h , pivoted in said body, and operated at one end by said shackle, and the ring H' at the other end, to contain 60 the seal, adapted, when the shackle is locked in place, to press tightly over the entrance to the key-hole of the lock, substantially as specified.

65 3. In a seal-lock, the combination, with the body A and the shackle E, pivoted at one end to the body, and adapted to be locked at

the other end in said body, and having an angle-arm, F, on the pivoted end thereof, of the locking-arm H, having the lever-arm h , pivoted in the body and projecting under the arm F of the shackle at one end, and the spring I, secured to the said arm h , and bearing at the end against the arm F, said locking-arm H being adapted to lock the seal in place, substantially as specified. 70

4. In a seal-lock, the combination, with the body A, having the head B, provided with an annular flange, a' , and a central opening therein, and the shackle pivoted to the said body and adapted at one end to enter and be 80 locked in the said opening in the head, of the locking-arm H, pivoted to said body, and having the ring H' , to carry the seal and bear against the circular lower side of the head when the shackle is locked in place, the upper 85 edge of the said ring being adapted to fit within the flange a' , as and for the purpose set forth. 75

5. The combination, in a seal-lock, with the body A, having the opening b at one end, and the shackle E, pivoted at the other end of said body, and adapted to enter at its free end said opening, of the spring-actuated dog D, pivoted in the body and adapted to engage the free end of the shackle, and the locking- 90 arm H, pivoted to the body and adapted to bear against the same over the opening b and hold the seal firmly in place over the said opening, substantially as specified. 95

6. The combination, with the body A, shackle 100 E, and the locking mechanism for the shackle, of the spring-actuated locking-arm for the seal, operated upon by said shackle, to be secured in place by the closing of the same, substantially as specified. 105

7. The combination, with the body A and the shackle, of the locking mechanism for said shackle, comprising the pivoted spring-actuated dog, and the seal-locking arm in operative connection with the shackle, to be forced 110 into position by the closing of the same, substantially as specified. 110

8. In a seal-lock, the combination, with the body having the seat a and the opening b in the center of the said seat, of the shackle E, pivoted to the said body at one end, and having the angle-arm F thereon, and adapted to be locked at the other end in said opening, and the locking-bar H, comprising the lever-arm h , pivoted to the body, and the ring H' , 115 adapted to bear on the said seat around the opening b therein, the said arm F on the shackle being adapted, when the shackle is closed, to bear upon the extremity of the arm or lever h and force the ring H' tightly against 120 the said seat to lock the seal in place, substantially as specified. 125

9. In a seal-lock, the combination, with the body A, having the opening b at one end and the hollow inclosed space B' on one side of 130 the said opening, of the dog D, pivoted within said hollow space, to be separated from the

other parts of the lock, the shackle having its free end entering the opening *b* and engaged by said dog, and the locking-bar *H* for the seal, closing at one end over the opening *b* and 5 operated upon by the closing of the shackle, substantially as specified.

In testimony that we claim the foregoing as

our own we have hereto affixed our signatures in presence of two witnesses.
